UNITED STATES PATENT OFFICE.

JOHN WEBER, OF TOLEDO, OHIO, ASSIGNOR TO THE AMERICAN NATIONAL COMPANY, OF TOLEDO, OHIO, A CORPORATION OF OHIO.

JUVENILE WAGON BODY.

Application filed November 3, 1924. Serial No. 747,414.

To all whom it may concern:

Be it known that I, JOHN WEBER, a citizen of the United States, and a resident of Toledo, in the county of Lucas and State of Ohio, have invented a new and useful Juvenile Wagon Body, which invention is fully set forth in the following specification.

This invention relates to juvenile wagon bodies of the detachable platform and body wall type, and particularly to the construction of the wall portion of such bodies.

Bodies of this class usually comprise a sheet metal platform member and a sheet metal body or side wall member of rectangular form for seating on or around the edge of the platform, the two members being secured together in a manner to facilitate detachment thereof, so that the bodies may be used either with or without the side wall part, as may be desired, and also to enable the separate members of a body to be compactly packed with other parts of a wagon for shipment or storage.

The primary object of the invention is the provision of a strong and durable body wall member for a wagon box of the class described, which will stand hard usage without springing or getting out of shape.

A further object of the invention is the provision of simple and efficient means for joining the ends of single or a plurality of side wall sections together, whereby not only an efficient but a strong and durable joint is secured and the side wall is otherwise strengthened.

The invention is fully described in the following specification, and while in its broader aspect it is capable of embodiment in different forms, a preferred embodiment thereof is illustrated in the accompanying drawings, in which,—

Figure 1 is a perspective view of a wagon box body embodying the invention, with a part broken away. Fig. 2 is an enlarged fragmentary perspective view of a joint portion of the side wall of the body. Fig. 3 is a top edge view thereof, with a part broken away, and Fig. 4 is a fragmentary perspective view of a different body embodying the invention, and with a part broken away.

Referring to the drawings, 1 designates the platform member of a juvenile wagon

body, and 2 the side or body wall member thereof, both of which, or at least the body wall member, are composed of sheet metal. In former cases, the platform is provided around its edge with a groove or recess for the lower edge of the side wall to seat in, and in other cases the body wall interengages in other ways in a detachable manner with the platform edge.

The body wall 2 is composed of one or more sheet metal pieces joined together at their meeting ends to conform to the shape and size of the platform, the pieces preferably being two in number and of U-shape longitudinally thereof with the joints formed by their meeting ends falling centrally in the ends of the body wall. The sheet metal of the body wall is formed with a roll 3 around its top edge to give strength and rigidity thereto and to improve its appearance, and is formed around its lower edge with a roll 4 to seat in or around the platform edge and to give strength and rigidity to the wall. The wall may also be provided intermediate its edges with beads 5, or panels 6, or other configuration for the purpose of both strength and ornamentation. The corners of the body wall are usually rounded.

The meeting end portions of the body wall are preferably joined by telescoping the respective edge rolls 3 and 4 and side-lapping the intermediate end portions of the metal for a short distance back from the joining ends, as shown in the drawings. The joined portions are then rigidly secured together by rivets 7, electric welding, or in any other suitable manner. This provides a joint which is simple to make and at the same time is exceedingly strong and rigid. The inner telescoping member of a pair is preferably reduced in size, as shown in Fig. 3, to facilitate joining.

It is preferable in practice to provide the body wall with a joint of this character centrally in each end, as the making of the body wall in two parts not only simplifies manufacture but the location of the points of jointure in this manner are found to add very materially to the strength and rigidity of the body wall. It is found in practice that if a body wall 2 with joints of the class described falling in the ends thereof, as shown in Fig. 1, is placed up-

right with one side resting on a support, a heavy man can stand on the other side intermediate its ends without springing such side or the end portions of the body wall, whereas if a body wall of the same construction, except that the joints are eliminated from the ends, is stood on in the same manner, the ends will spring outward and collapse and the top side wall will bow inward. It is, therefore, evident that the provision of the end joints adds materially to the strength of the body wall.

This added strength might not be of any considerable importance if the body wall were permanently attached to the platform, but with a wagon body of the class described where the body wall is detached from the platform both for shipping and at the will of the child or children using the same, it is of considerable importance. Such body walls usually receive rough usage due to their being thrown around and roughly handled when not in use on the wagon. It is not infrequent that a body wall when not in use on a wagon is turned up on its edge and used by the children and sometimes by older persons as a seat, and it must, therefore, be made strong in order to withstand such usage and maintain its shape so that it can be readily applied to the platform without necessitating springing it back into shape to fit the platform.

I wish it understood that my invention is not limited to any specific construction, arrangement or form of the parts, as it is capable of numerous modifications and changes without departing from the spirit of the claims.

Having thus described my invention,

what I claim as new and desire to secure 40 by Letters Patent is:

1. A juvenile wagon body having a detachable sheet metal side wall formed with upper and lower edge rolls and composed of a plurality of sections secured together 45 in end joining relation with the registering rolls of adjoining ends telescoping, and with the intermediate portions of the endslapping each other, and with one of said joints disposed centrally in each end portion of 50 the side wall, and means for securing the joined end portions of the body wall sections together.

2. A juvenile body wall having a detachable sheet metal side wall with upper and 55 lower edge rolls and divided into two U-shaped sections joined together at their meeting ends with the points of jointure disposed in the end portions of the body wall and formed by telescoping the registering 60 ends of the rolls and lapping the registering end portions of the sections intermediate the rolls, and means for securing the joined ends of the sections together.

3. A juvenile wagon body having a sheet 65 metal side wall composed of a plurality of sections provided with edge rolls secured together in end joining relation with the registering rolls telescoping, and with intermediate portions of the endslapping each 70 other, and means for securing the joined end portions together whereby the side walls may be subjected to heavy loads without the end portions collapsing.

In testimony whereof I have hereunto 75 signed my name to this specification.

JOHN WEBER.
